Filed Mar. 30, 1966, Ser. No. 1,687

Claims priority, application Germany Dec. 17, 1965

Term of patent 3½ years

(Cl. D34—15)

The figure is a perspective view of the toy spinning top showing my new design.

The characteristic features of my design reside in the combination of the top disclosed and of the specific aircraft representations and arrangement thereof within the dome-like cover, all as shown.

I claim:

The ornamental design for a toy spinning top, as shown and described.
